UNITED STATES PATENT OFFICE.

ANDREW A. PAYSEN, OF CLINTON, IOWA.

GAS-ENGINE.

1,081,252.

Specification of Letters Patent.

Patented Dec. 9, 1913.

Application filed April 23, 1912. Serial No. 692,668.

To all whom it may concern:

Be it known that I, ANDREW A. PAYSEN, a citizen of the United States, residing at Clinton, in the county of Clinton and State 5 of Iowa, have invented a new and useful Gas-Engine, of which the following is a specification.

This invention has reference to improvements in gas engines, and is more particularly directed to the valve structure for admitting the explosive mixture to the engine cylinder or cylinders and providing for the exhaust of the burnt gases therefrom.

It is the object of the present invention to 15 provide for the use of large ports and large valve openings, so that the intake of the charge and the exhaust of the burnt gases may be thorough, even though the engine be traveling at great speed, while all valve 20 noise is practically eliminated, the present invention doing away with all puppet valves, springs and other noise producing parts.

In accordance with the present invention 25 each port is controlled by rotatable valves, which latter are at least two in number for each port, and these valves may be made to move simultaneously in opposite directions, so as to largely increase the time during 30 which the valve is effectively open and to cause a rapid closing of the valve while the parts may be in continual progressive movement. To bring about this desirable condition each valve comprises two sleeves in con- 35 centric relation each provided with a port capable of moving into coincidence with the port of the other and into coincidence with a port leading to the interior of the engine cylinder. By making the last named port 40 large the sleeve ports may simultaneously move into coincidence one with the other and with the cylinder port, and this movement may be so timed that the port is open practically throughout one quarter cycle of 45 movement of the engine, considering the engine as of the usual four cycle type, while the port may be maintained in the closed condition during the remaining three quarters of the cycle, although the valves be in 50 constant motion.

The invention will be best understood from a consideration of the following detailed description taken in connection with the accompanying drawings forming a part 55 of this specification, with the further understanding that while the drawings show a

practical form of the invention it is susceptible of other practical embodiments of modified form, wherefore the invention is not confined to any strict conformity with 60 the showing of the drawings, but may assume various modified forms so long as such forms do not mark any material departure from the salient features of the invention.

In the drawings:—Figure 1 is an elevation of a multi-cylinder engine showing the invention applied. Fig. 2 is a plan view of the structure shown in Fig. 1. Fig. 3 is a section on the line 3—3 of Fig. 1 with some parts shown in elevation and distant parts 65 omitted. Fig. 4 is a section on the line 4—4 of Fig. 1 but drawn to a larger scale and omitting distant parts. Fig. 5 is an associated group of sectional views of the valves, illustrating the different phases of operation. Fig. 6 is an associated group of sectional views of a valve showing different 70 progressive phases of operation.

Referring to the drawings there is represented an engine 1 of the explosion type, 80 the representation being more or less schematic or typical of any suitable engine provided with power cylinders 2, of which two are shown, it being understood that the invention is applicable to a mono- or a multi-cylinder engine, as may be desired. The engine 1 is indicated as provided with a power shaft 3 and a fly wheel 4, as is customary in explosion engines. Each cylinder is shown as provided with a head 5 having ports 6 85 and 7 therethrough, which ports are indicated in Fig. 4 and for convenience of description the port 6 may be considered as the inlet port and the port 7 as the exhaust port. The port 6 communicates through a neck 8 with a cylindrical sleeve or casing 9 and the port 7 communicates through a neck 10 with a cylindrical sleeve or casing 11, the two sleeves or casings 9 and 11 constituting valve casings. When the invention 90 is applied to a single cylinder engine the valve casings 9 and 11 are comparatively short, but when the invention is applied to a multi-cylinder engine the casings 9 and 11 may extend over all the cylinders. As it 95 is customary to place the inlet ports on one side of each cylinder head and the exhaust ports on the other side thereof, the casings 9 and 11 are shown in the drawings as arranged on opposite sides of the common center line of the several engine cylinders.

Mounted within the casing 9 is a cylin-

drical valve member 12 and within the valve 12 is another cylindrical valve member 13 concentric with the valve 12 and both valves are concentric with the casing 9. Mounted within the casing 11 is a cylindrical valve member 14, and within the latter is another cylindrical member 15 arranged like the valve members 12 and 13. The valve member 12 is provided with a port 16, and the valve member 13 is provided with a port 17, and the valve members 14 and 15 have respective ports 18 and 19 like the ports 16 and 17. The several ports are each of a size to match the respective ports 6 and 7 and each valve member has as many ports therethrough as there are cylinders to the engine. The valve member 12 is continued through one end of the casing 9 and there carries gear wheels 20 and 21, respectively, while the valve member 13 has an axial extension 22 journaled in and extending through a portion 23 of a bracket 24 made fast to an adjacent cylinder 2, and beyond this bracket extension 23 the shaft-like axial extension 22 of the valve member 13 carries axially spaced gear wheels 25 and 26, respectively.

The valve member 14 is extended beyond the casing 11 at the end of the latter corresponding to that end of the casing 9 to which the valve 12 is extended, and the extended portion of the valve member 14 carries a gear wheel 27 in mesh with the gear wheel 20. The valve member 15 has an axial shaft-like extension 28 beyond the gear wheel 27 at which latter the valve member 14 terminates, and the outer end of the shaft extension 28 is provided with a journal bearing 29 carried by the bracket extension 23 and beyond this bearing 29 the shaft 28 carries a gear wheel 30 meshing with the gear wheel 25.

The gear wheels 21 and 26 are bevel gear wheels and both mesh with respectively opposite sides of a bevel gear wheel 31 mounted on one end of a shaft 32 having a journal bearing 33 carried by the bracket 24, while the other end of the shaft 32 has a step bearing 34 on a part of the engine frame and adjacent said step bearing carries a bevel gear 35 meshing with another bevel gear 36 on the power shaft 3 of the engine. The arrangement is such that when the engine is running, motion is transmitted from the shaft 3 through the bevel gears 35 and 36 to the shaft 32, and thence to the bevel gear 31. By the said bevel gear 31 motion is transmitted to the two bevel gear wheels 21 and 26 causing them to rotate in opposite directions. Motion is at the same time transmitted from the valve member 12 by way of gear wheels 20 and 27 to the valve member 14 and motion is transmitted from the shaft extension 22 by way of the gear wheels 25 and 30 to the valve member 15,

the arrangement causing the valve members 14 and 15 to rotate in opposite directions and also causing the valve members 12 and 13 to rotate in opposite directions, and while the direction of rotation of the matching valve members of the two sets is opposite one to the other, this particular feature is not material to the operation of the system.

In Fig. 5 the several phases of operation of the valves in time with the several cycles of the engine are shown and Fig. 5 also illustrates the relative angular displacement of the ports in the rotatable valves in a four cycle engine. In Fig. 5 the valves are shown as in four groups, A, B, C, D, and it may be assumed that the valve structures on the left hand side of the several groups represent the intake valve structure of the engine, while those on the right hand side represent the exhaust valve structure of the engine, and for convenience of description it will be assumed that the several groups indicate the intake and exhaust valve structures of a single cylinder. In group A the valves 12 and 13 are turned about the axis of rotation until their respective ports 16 and 17 are in coincidence and also coincide with the passage through the neck 8 leading to the intake port 6 of the engine, which port is shown in Fig. 4 only. Considering the showing of the intake valve structure in group A with reference to a clock face, the ports 16 and 17 are in the six o'clock position. Under these conditions the valves 14 and 15 are so positioned that the port 18 of the valve 14 is in the nine o'clock position and the port 19 of the valve 15 is in the three o'clock position. Suppose that the valve 12 is turning counter-clockwise and the valve 13 is turning clockwise. Suppose, further, that the valve 14 is rotating clockwise as the valve 15 is rotating counter-clockwise. The position of the parts shown in group A represents the intake stroke of the piston of the engine at about midway of such intake stroke when the intake valve is fully open, the exhaust valve being fully closed. In a four cycle engine the intake stroke is followed by the compression stroke and the intermediate position of the valves during such stroke is shown in group B. The valve 12 has rotated sufficiently to carry its port 16 to the three o'clock position and the valve 13 has rotated sufficiently to carry its port 17 to the nine o'clock position, while the two valves 14 and 15 have rotated sufficiently to bring their ports both to the twelve o'clock position. In these positions both the intake and exhaust ports of the engine are closed and the compression stroke may be completed and the charge exploded in the usual manner, while the piston of the engine starts on the power stroke, and when the power stroke reaches about its mid-point, the valves have turned until the

ports 16 and 17 are in the twelve o'clock position and the ports 18 and 19 are in the three o'clock and nine o'clock positions, respectively, as shown in group C, the engine ports still being closed. Ultimately the scavenging stroke of the engine piston commences and by the time it has reached its mid-point the valve ports are in the operative positions shown in group D, the ports 16 and 17 having reached the nine o'clock and three o'clock positions, respectively, and the ports 18 and 19 being in coincidence with the exhaust port 7, so that the burnt gases are escaping. The movement of the two concentric valves on either the intake or exhaust valve structure is illustrated in Fig. 6 where the valves which may be taken as the valves 12 and 13 are shown at *a* so positioned that the ports 16 and 17 are about to begin to overlap. At *b* the ports are shown as further overlapping, and at *c* the two ports are shown as in full coincidence one with the other and with the passage through the neck 8. The movement of the valves is so timed that the steps illustrated in Fig. 6 take place in order and the valve members are carried to the full closed position progressively during the respective movements of the engine piston, so that the port begins to open, is carried to the full open position, and then to the full closed position during the one movement of the piston. Since there are two oppositely moving openings in the two valves, the full open position is more readily attained than where a single valve is employed and the closing is also more rapid.

To take up wear and to prevent leakage, the valves may be tapered slightly in the direction of their length to thereby maintain a snug fit without undue friction.

The valves are shown in the drawings as continuously rotating, but a similar effect is possible with the valves rocking, but the rotating form of valve is to be preferred, since all sudden changes in motion such as are caused by rocking movements are detrimental to the best effects.

In the particular showing of the drawings the inner intake valve 13 is hollow and is divided off by diaphragms 37 into separate chambers for each cylinder and both valves 12 and 13 are provided with ports 38 and 39, respectively, for each cylinder, these ports being arranged for coincidence with a pipe 40 opening through the casing 9 in such position as to be matched by the ports 38 and 39 when in coincidence during the rotative movement of the valves 12 and 13. The pipes 40, one for each cylinder, may be carried to a suitable source of fuel supply, such as a carburetor, so that each cylinder may receive a charge without respect to the other cylinders. It will be understood, of course, that the valve 13 may be longitudinally con-

tinuous throughout the range of all the cylinders and thereby form a reservoir from which the fuel is drawn whenever the intake port of the cylinder and the ports 16 and 17 match. The valve 15 is hollow and this hollow portion may be continuous throughout the range of the cylinders and may be utilized for the escape of the gases of combustion from all the cylinders, such gases being disposed of by any suitable means usually employed in connection with explosion engines.

It will be understood that other arrangements for the intake of fuel and exhausting of the burnt gases may be brought about by a proper construction of the valves 12 and 13 and the valves 14 and 15, as well as the casings 9 and 11, since these parts may be otherwise constructed than shown in the drawings without interfering with the use of oppositely rotating valve members coacting to prolong the effective opening of the valves during the period of time to which the opening and closing of the valves with respect to the engine ports is restricted.

The valve structure of the present invention is useful in connection with the intake and exhaust of steam engines, and therefore is not of necessity limited in its use to explosion engines.

What is claimed is:—

1. An engine provided with a power cylinder and power shaft, intake and exhaust valve structures each comprising a casing having a substantially cylindrical bore provided with a port communicating directly and independently of the port of the other casing with the interior of the power cylinder, a pair of concentrically arranged valves in each casing and each provided with a port movable into coincidence one with the other and with the port in the casing, both valves extending beyond the same end of the casing and the inner valve extending beyond the corresponding extended end of the other valve, and driving connections between the power shaft at one end of the engine and both valves at the same end of the engine where extended beyond the corresponding end of the casing, said driving connections being constructed to cause the rotation of the valves simultaneously in opposite directions.

2. In a multi-cylinder engine, intake and exhaust valve structures each comprising a valve casing and an inner and outer valve member arranged concentrically within the casing, said valve members being each provided with as many ports as there are cylinders and the casing being similarly provided, and means for rotating the valve members within each casing in opposite directions one to the other to bring the valve ports into coincidence one with the other and with the port in the casing, the inner valve of the intake valve structure being provided

with chambers individual to the cylinders, and the inner valve of the exhaust valve structure having its interior free from obstruction to receive the exhaust and convey it to one end of the engine.

In testimony, that I claim the foregoing

as my own, I have hereto affixed my signature in the presence of two witnesses.

ANDREW A. PAYSEN.
